UNITED STATES PATENT OFFICE.

THOMAS DE C. RUTH, OF NEWARK, NEW JERSEY, ASSIGNOR TO ROBERT J. EMORY & COMPANY, OF NEWARK, NEW JERSEY, A COPARTNERSHIP.

SPOOLING-MACHINE.

No. 870,850.

Specification of Letters Patent.

Patented Nov. 12, 1907.

Application filed October 1, 1906. Serial No. 336,928.

To all whom it may concern:

Be it known that I, THOMAS DE C. RUTH, a citizen of the United States, residing in Newark, Essex county, State of New Jersey, have invented a new and useful 5 Improvement in Spooling-Machines, of which the following is a specification.

This invention relates to spooling machines and particularly to mechanism for reversing the movement of the traverse bar of wire-spooling machines.

10 In order to insure the smooth winding of the wire upon the spool it is customary to provide wire-spooling machines with guides mounted on a sliding bar which is automatically reciprocated in a path parallel to the axis about which the spool is rotated during the operation 15 of winding the wire on the spool. It is necessary to vary the range of movement of this bar from time to time and ordinarily the variation of this range of movement is accomplished by removing a gage-plate from the reversing mechanism and substituting another 20 gage-plate of different length.

The present invention has for its object the provision of a simple reversing mechanism for the traverse bar by means of which the range of movement may be quickly altered without making any change in the parts of the 25 reversing mechanism.

In the drawings forming a part of this specification, in which corresponding parts are indicated by similar characters of reference, I have illustrated a preferred embodiment of my invention, but it is to be understood 30 that variations in the details of construction may be resorted to without exceeding the scope of the invention, which is clearly defined in the appended claims.

In the drawings: Figure 1 is a perspective view of a portion of a wire-spooling machine of a well known 35 type having the improved reversing mechanism for the traverse bar applied thereto. Fig. 2 is a plan view of the device by which the range of movement of the traverse bar is determined. Fig. 3 is a view in elevation of the structure shown in Fig. 2, parts being broken 40 away or shown in section.

Referring to the drawings by the reference characters, F designates a portion of the main frame of the machine, and S indicates a driving shaft to which power is applied in any suitable manner.

45 1-1 are spindles upon which the spools on which the wire is to be wound are secured and rotated by belts (not shown) on small pulleys 2 fixed on the spindles. Adjacent to each spindle a guiding device 3 is provided, each of these guides being mounted on the traverse bar 4, which is slidably mounted in brackets 5 on the frame of the machine. Movement is imparted to the traverse bar 4 from a screw 6 having oppositely threaded portions 7 and 8. This screw 6 is driven from the shaft S by means of the friction wheel 9 and 50 the disk 10, the former being mounted on the shaft S

and the latter being fast on the end of the screw 6. The friction wheel 9 is preferably adjusted by means of the screw 11 to vary the rate of rotation imparted to the screw 6. In order to transmit motion to the traverse bar 4 from the feed screw 6, two half-nuts 12 and 13 60 are mounted on arms 14 and 15 made fast on the traverse bar and so positioned that when the half-nut 12 engages the threaded portion 7 of the screw the half-nut 13 is out of engagement with the screw, but is adapted to be brought into engagement with the threaded 65 portion 8 thereof as soon as the half-nut 12 is thrown out of engagement with the threaded portion 7. As will be seen on inspection of Fig. 1, the traverse bar is moved to the left when the half-nut 12 is in engagement with the threaded portion 7 of the screw, and when the 70 half-nut 13 is brought into engagement with the threaded portion 8 of the screw the traverse bar is moved to the right.

In order to effect the reversal of movement of the traverse bar at each end of its range of movement, 75 mechanism is provided to throw one of the half-nuts out of engagement with the corresponding threaded portion of the feed-screw and to throw the other half-nut into engagement with the oppositely threaded portion of the feed-screw. This mechanism comprises 80 an arm 16 rigidly secured to the traverse bar and the device illustrated in detail in Figs. 2 and 3. This device comprises a bed 17 having a groove 18 with undercut sides formed in its upper surface, a slide 19 arranged for reciprocation in the groove 18, adjustable stops to 85 limit the movement of the slide 19, and devices carried by the slide to shift the arm 16 at each end of the range of movement of the traverse bar so as to throw the active half-nut out of engagement with the feed-screw and throw the other half-nut into engagement therewith. 90 The stops by which the movement of the slide 19 is controlled consist of a pair of nuts 20 and 21 mounted on a screw 22 supported on the underside of the bed 17 in suitable brackets 23. These nuts are engaged by a collar 24 encircling the screw 22 supported on a bracket 95 25 which is secured to the slide 19 and works in a slot in the bed 17. Projecting upward from the slide 19 above the bracket 25 is a flat lug 26 which preferably has beveled edges, as shown in Fig. 2. Springs 27 and 28 are so arranged that they co-operate with the lug 26 in forming pockets to receive the arm 16 carried by the 100 traverse bar.

When, the arm 16 lies between the lug 26 and the spring 27 the half-nut 12 is in engagement with the threaded portion 7 of the feed screw and movement to the left is imparted to the traverse bar. As the traverse bar moves to the left the collar 24 which is carried 110

by the slide 19 moves toward the stop nut 20 and when the collar 24 engages the stop nut motion of the slide 19 is arrested. The movement of the traverse bar to the left continues, however, as long as the half-nut 12 5 remains in engagement with the feed-screw and, as the traverse bar continues to move to the left, the arm 16 is forced forward against the spring 27, which is thereby forced out of contact with the lug 26. As soon as the arm 16 passes the lug 26 the pressure of the free end of 10 the spring 27 against the arm throws the arm 16 over against the spring 28 and this movement of the arm 16 rocks the traverse bar 4 sufficiently to throw the half-nut 12 out of engagement with the feed-screw and to bring the other half-nut 13 into engagement with the 15 threaded portion 8 of the feed screw. The shifting of the half-nuts 12 and 13 immediately reverses the direction of movement of the traverse bar and the arm 16 then lies in the pocket between the spring 28 and the lug 26 and the movement of the traverse bar to the right 20 imparts movement to the slide 19 in the same direction. This movement of the slide 19 continues until the collar 24 carried by the slide is arrested by the stop nut 21, when the movement of the slide ceases and the continued movement of the traverse bar and the arm 25 16 to the right forces the spring 28 out of engagement with the lug 26 and carries the traverse bar beyond the lug 26. As soon as the arm 16 is moved far enough to the right to pass out of contact with the lug 26 the spring 28 throws the arm 16 over toward the spring 27 30 and brings the half-nut 12 again into engagement with the threaded portion 7 of the feed-screw; and throws the half-nut 13 out of engagement, thus reversing the direction of movement of the traverse bar and starting it on its return movement toward the left.

35 From the foregoing description and the accompanying drawings it will be seen that the range of movement of the traverse bar is determined by the range of movement allowed the slide 19 on the bed 17 and that the range of movement of this slide is controlled 40 by means of stop nuts 20 and 21 on the screw 22. Consequently, in order to vary the range of movement of the traverse bar it is only necessary to alter the position of one or both of the nuts 20 or 21 and it is unnecessary to change any element of the reversing mechanism.

45 The adjustment of the nuts 20 and 21 can be made in-

stantly without stopping the machine and by an unskilled operative.

Having thus described my invention, what I claim as new and desire to secure by Letters Patent is:

1. In a spooling machine, the combination with a reciprocating traverse bar, of mechanism for imparting movement to the traverse bar and devices for reversing the direction of movement of the traverse bar at each end of its range of movement, said reversing devices comprising a slide, an arm carried by the traverse bar and engaging the slide, adjustable stops to limit the movement of the slide, and means carried by the slide for shifting the position of said arm after movement of the slide has been arrested by either of the stops therefor. 50

55 2. In a spooling machine, the combination with a reciprocating traverse bar, of mechanism for imparting movement to the traverse bar and devices for reversing the direction of movement of the traverse bar at each end of its range of movement, said reversing devices comprising a slide, adjustable stops to limit the movement of the slide; an arm carried by the traverse bar and extending toward the slide, and devices mounted on slide and engaged by said arm whereby movement is imparted to the slide from said arm and whereby said arm is shifted after the slide engages each of the stops to limit its movement. 60

65 3. In a spooling machine, the combination with a reciprocating traverse bar, or of mechanism for imparting movement to the traverse bar, said mechanism including two continuously operative driving elements, one adapted to impart movement to the traverse bar in one direction and the other adapted to impart movement to the traverse bar in the opposite direction, and shiftable connections between said driving elements and the traverse bar so arranged that the connections with one of said driving elements only can be in operative position at a given time, 70 and devices for reversing direction of movement on the traverse bar at each end of its range of movement, said devices comprising a slide, adjustable stops to limit the movement of the slide, a lug carried by the slide, a pair of bent springs extending in opposite directions and engaging the lug on both sides of the arm extending from said traverse bar toward said slide and adapted to engage said springs, whereby said arm is shifted at the engagement of said slide with each of said stops and the traverse bar is rocked to throw into operation the connections between the traverse bar and one of the driving elements and throw out of operation the connection between the traverse bar and the other driving element. 75

80 In testimony whereof, I have signed my name in the presence of two witnesses.
